2-CYCLOHEXYL AND 2-CYCLOHEXYLIDENE-
1-(3'-PIPERIDINO-PROPYL)-CYCLOHEX-
ANOLSKarl Miescher, Richen, and Adrian Marxer, Basel,
Switzerland, assignors to Ciba Pharmaceutical
Products, Inc., Summit, N. J.No Drawing. Application December 27, 1950, Se-
rial No. 203,022. In Switzerland February 1,
1950

1 Claim. (Cl. 260—294.7)

1

The present invention is for the manufacture of 2-cyclohexylidene- and 2-cyclohexyl-1-(3'-piperidino-propyl)-cyclohexanol of the formulae

and

respectively, and salts thereof.

These new compounds are powerful spasmolytics, and as compared with comparable known compounds they are especially active against Parkinson's disease. They are useful as medicaments.

The aforesaid cyclohexanols are obtained by reacting an N-[1-halogen-propyl-(3')-1-piperidine with a metal and then with 2-cyclohexylidene-cyclohexanone or 2-cyclohexyl-cyclohexanone, and if desired hydrogenating the resulting 2-cyclohexylidene-1-(3'-piperidino-propyl)-cyclohexanol. As metals there may be used primarily magnesium, yet also cadmium or zinc are suitable. In the reaction, for example with magnesium, the corresponding organometal compound is formed and then the latter reacts with the above mentioned cyclohexanones. It is of advantage to activate the metal; thus, for example, magnesium may be activated with the aid of a small quantity of iodine and/or an alkyl halide.

By the process of the invention metal compounds of the above cyclohexanols are obtained which may be converted into the free cyclohexanols for example, by reaction with a mineral acid. In this way the usual salts of the bases are obtained, from which salts the free bases can be obtained in the usual manner. From the free bases salts can be prepared with acids such, for example as hydrohalic acids, sulfuric acid, nitric acid, phosphoric acid, thiocyanic acid, acetic acid, propionic acid, oxalic acid, malic acid, citric acid, benzoic acid, methane sulfonic acid, ethane sulfonic acid, oxy-ethane sulfonic acid, benzene sulfonic acid or toluene sulfonic acid.

The following examples illustrate the inven-

5

tion, the parts being by weight unless otherwise stated and the relationship of parts by weight to parts by volume being the same as that of the gram to the cubic centimeter:

Example 1

12.0 parts of magnesium are covered with a small quantity of absolute ether. Ethyl bromide is added to initiate the reaction, and then 46.8 parts of N-[1-chloropropyl-(3')-1-piperidine in 25 parts by volume of absolute benzene and 75 parts by volume of absolute ether are added rather quickly while stirring and gently heating. After stirring for 4 hours in a water bath at 50° C., 42.8 parts of 2-cyclohexylidene-cyclohexanone are added in small portions and the reaction mixture is maintained for a further 5 hours at 50° C. The reaction product is then mixed with dilute hydrochloric acid, whereupon the crystalline, sparingly soluble hydrochloride of 2-cyclohexylidene-1-(3'-piperidino-propyl)-cyclohexanol of the formula

precipitates from the hydrochloric acid solution. 30 After recrystallisation from a mixture of alcohol and ethyl acetate it melts at 223-225° C. By agitating the hydrochloride with ether and potassium carbonate there can be obtained the free base which boils at 146-148° C. under 0.07 mm. 35 pressure.

Example 2

6.4 parts of 2-cyclohexylidene-1-(3'-piperidino-propyl)-cyclohexanol hydrochloride are 40 agitated in 160 parts by volume of alcohol with 0.5 part of platinum oxide and hydrogen until the calculated quantity of hydrogen has been absorbed. After removing the catalyst by filtering with suction, the alcohol is distilled under 45 reduced pressure and the residue is treated with potassium carbonate solution and ether. From the ethereal solution there is obtained 2-cyclohexyl-1-(3'-piperidino-propyl)-cyclohexanol of the formula

55

3

which boils at 152-153° C. under 0.07 mm. pressure. By treating the free base with an alcoholic solution of hydrochloric acid the hydrochloride melting at 231-233° C. is obtained.

Example 3

The procedure is the same as that described in Example 1, except that, instead of the 2-cyclohexylidene-cyclohexanone, 43.0 parts of 2-cyclohexyl - cyclohexanone are used. The 2-cyclohexyl - 1 - (3' - piperidino - propyl) - cyclohexanol described in Example 2 is obtained.

What is claimed is:

A member selected from the group consisting of 2 - cyclohexylidene -1- (3' - piperidino - propyl) - cyclohexanol of the formula

5

and 2 - cyclohexyl - 1 - (3' - piperidino - propyl) - cyclohexanol of the formula

10 and the salts of said hexanols.
